CLAIM

We claim the ornamental design for a fitness device display panel, as shown and described.

DESCRIPTION

FIG. 1 is a front, side perspective view of a fitness device display panel;

FIG. 2 is a rear, side perspective view of the fitness device display panel of FIG. 1;

FIG. 3 is a front view of the fitness device display panel of FIG. 1;

FIG. 4 is a rear view of the fitness device display panel of FIG. 1;

FIG. 5 is a first side view of the fitness device display panel of FIG. 1;

FIG. 6 is a second side view of the fitness device display panel of FIG. 1;

FIG. 7 is a top view of the fitness device display panel of FIG. 1; and,

FIG. 8 is a bottom view of the fitness device display panel of FIG. 1.

The ornamental design that is claimed is shown in solid lines in the drawings. The dashed lines shown in FIGS. 1 through 8 are included for the purpose of illustrating environmental elements only and form no part of the claimed design.

1 Claim, 7 Drawing Sheets
